F.M. Howe

UNITED STATES PATENT OFFICE

FRED M. HOWE, OF WELLSBORO, PENNSYLVANIA.

PISTON RING.

Application filed November 30, 1921. Serial No. 518,932.

To all whom it may concern:

Be it known that I, FRED M. HOWE, a citizen of the United States, residing at Wellsboro, in the county of Tioga and State 5 of Pennsylvania, have invented new and useful Piston Rings, of which the following is a specification.

This invention aims to provide a novel form of auxiliary ring, adapted to be placed 10 between the main ring on the piston of an internal combustion engine and the piston, for the purpose of preventing oil from passing the main ring, and for the further purpose of pressing the main ring outwardly, 15 so that it will have a firm bearing on the wall of the cylinder.

It is within the province of the disclosure 20 to improve generally and to enhance the utility of devices of that type to which the invention appertains.

With the above and other objects in view, which will appear as the description proceeds, the invention resides in the combination and arrangement of parts and in 25 the details of construction hereinafter described and claimed, it being understood that, within the scope of what is claimed, changes in the precise embodiment of the invention shown can be made without departing from the spirit of the invention.

In the drawings:

Figure 1 shows in longitudinal section, a portion of the piston of an internal combustion engine equipped with the device 35 constructed in accordance with the invention; Figure 2 is a cross section on the line 2-2 of Figure 1; Figure 3 is fragmental plan showing a portion of the blank out of which the auxiliary ring is formed; Figure 4 is a cross section showing a modification; Figure 5 is a cross section showing a further modification; Figure 6 is a fragmental elevation showing another modification; Figure 7 is cross section on the 40 line 7-7 of Figure 6; Figure 8 is a cross section depicting another modification; Figure 9 is a cross section wherein a further modification is shown; Figure 10 is a cross section disclosing another modified form of the invention; Figure 11 is a cross section wherein a further modification appears; Figure 12 is a cross section delineating another modification; Figure 13 is a cross section showing a modified form of the invention.

Referring to Figures 1, 2 and 3, the numeral 2 denotes the piston of an internal combustion engine, the piston having a groove 3 wherein a main ring 4 is seated, the construction being common and well understood.

A resilient auxiliary ring 5 is located in the groove 3 and is interposed between the main ring 4 and the piston 2, the auxiliary ring 5 being divided as indicated at 6.

The auxiliary ring 5 is fashioned from a resilient strip 7 preferably of metal, the strip being provided in its edges with inwardly extended slits 8 defining tongues 9. The strip 7 is bent along longitudinal lines 70 10 to define a body 11, and to cause the tongues 9 to form flanges which extend outwardly, the body 11 bearing against the piston 2, as shown in Figure 1, and the outwardly extended resilient tongues 9 bearing 75 against the main ring 3. The construction is such that the passage of oil behind the main ring 4 will be rendered difficult, and the main ring will be sustained in the position shown in Figure 1 to afford a secure 80 engagement between the main ring and the wall of the cylinder wherein the piston 2 works.

In Figure 4, the body appears at 12 and the flange-forming tongues at 14. In this 85 form of the invention, the tongues 14 project inwardly and engage the piston 2 whereas, the body 12 cooperates with the ring 4.

In Figure 5, the body is shown at 15, and is provided along one edge with inwardly extended flange-forming tongues 16 90 adapted to cooperate with the body being provided along its opposite edge with outwardly extended flange-forming tongues 17 adapted to cooperate with the main ring. 95

In Figures 6 and 7, the body is shown at 18 and is provided on one edge with flange-forming tongues 19 which project inwardly, as shown in Figure 7, the body 18 cooperating with the main ring, and the tongues 100 19 cooperating with the piston.

In Figure 8, the body is shown at 20, and is provided along one edge with flange-forming tongues 21, the body being adapted to cooperate with the piston, whereas the 105 tongues 21 engage the main ring.

In Figure 9, the body appears at 22 and is provided along one edge with flange-forming tongues 23 being disposed at the opposite edge of the body, from the disclo- 110

sure in Figure 8. The tongues 23 bear against the piston, the body 22 engaging the ring.

In Figure 10, the body is shown at 24, 5 and is provided along both of its edges with flange-forming tongues, denoted by the numerals 25 and 26, the tongues engaging the piston, whereas the body 24 cooperates with the main piston ring.

10 In Figure 11, the body is shown at 27 and is supplied along one edge with inwardly inclined flange-forming tongues 28, the body being provided along its opposite edge with inwardly inclined flange-forming tongues 15 29, the tongues 28 bearing against the piston, and the tongues 29 bearing against the main ring.

In Figure 12, the body of the auxiliary ring is marked by the numeral 30 and is 20 provided along its edges with outwardly projecting flange-forming tongues 31 and 32. The body 30 cooperates with the piston,

whereas the tongues 31 and 32 engage the main piston ring.

In Figure 13, the body is denoted by the 25 numeral 50, and is provided along one edge with a flange 51, the construction being that delineated in Figure 7, aside from the fact that the flange 51 is not slit to form tongues. In this connection it is to be observed that, 30 if desired, the slits may be omitted in the other forms of the invention.

What is claimed is:—

An auxiliary piston ring or piston ring expander, comprising a strip of spring metal 35 having transversely extending edge tongues disposed at an angle to the body.

In testimony that I claim the foregoing as my own, I have hereto affixed my signature in the presence of two witnesses.

FRED M. HOWE.
